UNITED STATES PATENT OFFICE.

MAX O. PUHL, OF FREDERICKSBURG, TEXAS.

EMERGENCY-DOOR FOR SAFES.

1,243,101.

Specification of Letters Patent. Patented Oct. 16, 1917.

Application filed November 22, 1915. Serial No. 62,829.

To all whom it may concern:

Be it known that I, MAX O. PUHL, a citizen of the United States, residing at Fredericksburg, in the county of Gillespie, State 5 of Texas, have invented certain new and useful Improvements in Emergency-Doors for Safes; and I do hereby declare the following to be a full, clear, and exact description of the invention, such as will enable 10 others skilled in the art to which it appertains to make and use the same.

This invention relates to emergency doors for safes.

The object of the invention is to provide 15 an improved arrangement including a supplemental door which will automatically move to closed position when the main door is opened to its limit.

With the above and other objects in view 20 the invention consists in the details of construction and in the arrangement and combination of parts to be hereinafter more fully described and particularly pointed out in the appended claims.

25 In describing the invention in detail reference will be had to the accompanying drawings wherein like characters of reference denote corresponding parts in the several views, and in which—

30 Figure 1 is a view in elevation of a safe showing both the normal door and the emergency door in open position;

Fig. 2, a view similar to Fig. 1 with the emergency door in closed position and the 35 contact plate operated to close the electric circuit;

Fig. 3, a section on the line 3—3 of Fig. 1; Fig. 4, a section on the line 4—4 of Fig. 2, with the normal door operated to a position 40 to close the electric circuit;

Fig. 5 is a detail view showing the electrically operated latch for releasing the emergency door, the door casing being shown in section as also the stud over which the 45 latch engages, and

Fig. 6, a diagrammatic view of the electric circuits employed in the device.

Referring to the drawings A indicates a safe or vault provided with the usual door 50 opening 10 adapted to be closed by a hinged door 11 all in the usual and well known manner. Mounted on the front of the safe A and extending to one side of the latter is a casing 12 in which is slidably mounted an 55 emergency door 13 normally held in closed position with respect to the opening 10 by

means of springs 14 interposed between the outer end of the casing and the door 13. Pivoted to the door 13 is a latch 14' adapted to engage over a stud 15 on the casing 12 for the purpose of holding the door 13 in open position against the influence of the springs 14. Mounted on the inner wall of the casing above the latch 14' is a magnet 16 adapted to attract the latch 14' when energized for the purpose of moving the latch to release position and permitting the springs 14 to close the door 13. The magnet 16 is included in an electric circuit emanating from a battery or other electrical source 70 17. One pole of this source is connected to the magnet 16 by means of a wire 18 while the other pole is connected to a contact 19 by a wire 20. Another contact 21 spaced from the contact 19 is connected to the magnet 16 by means of a wire 22. The contacts 19 and 21 are adapted to be connected by means of a contact plate 23 which is normally held out of engagement with the contacts 19 and 21 by means of springs 24. 80 This plate 23 is disposed just in front of the door opening 10 so that when a person approaches the opening 10 and his weight is disposed upon the plate 23 the latter will be forced into engagement with the contacts 85 19 and 21 and close the electric circuit to energize the magnet 16. The energization of the magnet 16 will of course move the latch 14' to release position and permit the door 13 to move to closed position under 90 the influence of the springs 14. The magnet 16 is also adapted to be energized by a predetermined opening movement of the door 11, said door being provided with a contact 25 adapted to engage a contact 26 on the 95 safe A when the door has been opened a sufficient distance. This contact 25 is connected to the wire 20 by means of a wire 27, while the contact 26 is connected to the wire 22 by means of a wire 28. By this 100 construction it will be obvious upon reference to Fig. 6 that when the contacts 25 and 26 are engaged the magnet 16 will be energized to release the door 13.

The structure just described is particularly useful in guarding against robbery in that employees can effect the closing of the door 12 in a quick and mysterious manner when threatened. The door 12 carries an arm 29 provided with a contact 30 adapted 110 to engage a contact 31 on the safe A when the door 12 is closed for the purpose of

2
closing a suitable electric circuit to sound a suitable alarm.

What is claimed is:

1. The combination with a safe having a door opening and a door constructed and arranged for movement into and out of the opening, a closure movable into and out of position across the door opening when the door is in open position, means for moving the closure into closing position, a latch for holding the closure normally in open position and means operable by the door when in wide open position for releasing the latch.
- 10 2. The combination with a safe having a door opening and a door constructed and arranged for movement into and out of said

opening, of a closure movable into and out of position across the door opening when the door is in wide open position, a latch for holding the closure in open position, 20 means for moving the closure into closed position when the latch is disengaged and means constructed and arranged for operation by a person adjacent the door opening for releasing the latch.

25 In testimony whereof, I affix my signature, in the presence of two witnesses.

DR. MAX O. PUHL.
